FLUID ELEVATOR

Jeddy D. Nixon, Houston, Tex., assignor to S. S.
McClendon, Jr., Houston, Tex., as trustee

Application February 27, 1933, Serial No. 658,882

6 Claims. (Cl. 103—248)

This invention relates to a fluid elevator.

An object of the invention is to provide apparatus whereby liquid in a well may be delivered to the ground surface through the agency of an operating fluid under pressure. The invention relates to certain improvements over that type of apparatus for a similar purpose disclosed by my copending application on Method and apparatus for producing liquid from wells filed June 10, 1932, under Serial No. 616,487.

Another object of the invention is to provide apparatus of the character described of such construction that the liquid to be recovered from the producing formation may be trapped, or separated from the cognate liquid in the well, in successive loads or quantities and an operating fluid, such as air or gas, under pressure, applied to said trapped or separated quantities or loads to expel them successively from the well; an important feature of the invention resides in the novel means for restraining or cutting off the operating fluid so that the same will be expended only while actually expelling a load of liquid from the well, said means comprising a novelly constructed valve mechanism particularly designed for the purposes stated.

Another object is to provide an apparatus of the character described wherein special means has been provided for excluding the operating fluid from the producing formation of the well. Another object is to provide, in apparatus of the character described, novel means for automatically controlling the application of the operating fluid.

Another object of the invention is to provide, in apparatus of the character described, a novel type of valve of such construction and mounted in such novel manner that it may be easily opened and closed to control the application of the operating fluid to the loads of entrapped liquid.

The invention also includes a novel type of dash pot.

With the above and other objects in view the invention has particular relation to certain novel features of construction, operation, and arrangement of parts, an example of which is given in this specification and illustrated in the accompanying drawings, wherein:

Figure 1 shows a vertical sectional view of the lower end of the apparatus.

Figure 2 shows a similar view of the upper end thereof.

Figure 3 shows a vertical sectional view of the upper portion of the float chamber showing the valves and valve operating mechanism.

Figure 4 shows an enlarged vertical sectional view of the controlling valve mechanism employed.

Figure 5 shows a vertical sectional view showing an intermediate section of the float chamber illustrating a novel type of dash pot mounted therein.

Figure 6 shows an enlarged fragmentary vertical sectional view of the dash pot.

Figure 7 shows an enlarged vertical sectional view, showing the lower end of the float chamber and the packing assembled therewith and located beneath said chamber also showing the inlet valve for controlling the inlet of liquid into said chamber, and

Figure 8 shows an enlarged vertical sectional view of the upper portion of the float chamber taken on the line 8—8 of Figure 3.

Referring now more particularly to the drawings wherein like numerals of reference designate the same parts in each of the figures the numeral 1 designates the well casing which is set at the desired depth in the well. A suitable inflow pipe 2 may be provided whose lower end extends down the required distance into the liquid to be lifted and a suitable packer as 3 may be set between the casing 1 and the inflow pipe 2 as shown in Figures 1 and 7. This packer is in the form of an upwardly opening cup ring, one or more of which may be used as desired, only one being shown. Any type of packer suitable for the purpose may be used. Above the packer 3 there is a suitable housing 4 within which there is a float chamber 5. The upper end of the inflow pipe 2 may be suitably connected into the lower end of the housing 4, and within the float chamber 5 there is a suitable valve cage 6 preferably connected to the upper end of the inflow pipe 2 and clamping the valve seat 7 in place. The inflow of liquid through the pipe 2 and seat 7 is controlled by the upwardly opening valve 8 which is confined by said cage. The lower end of the pipe 2 may have a suitable nipple 9 attached thereto whose lower end has the inlet opening 10.

Attached to the upper end of the housing 4 and closing the same there is a head 11, and leading upwardly from this head to the ground surface there is an eduction tube 12 which continues on down into and through the chamber 5 and whose lower end terminates above but adjacent the lower end of the float chamber.

There is a bore 13 through the head 11 which connects that portion of the eduction tube 12, be-

neath the head 11, with the tube 12 above the head.

The head 11 has the inlet passageway 14 therethrough connected into the upper end of which there is the upstanding pipe 15, whose upper end may have a strainer 16 thereon if desired. It is contemplated that the housing 4 will be surrounded with oil and the level of this oil will stand some distance above the head 11 to the end that the operating fluid will be excluded from the packing 3. The pipe 15 is of such length that the screen 16 will be above the level of the oil. A trap will thus be formed so that any sediment falling through the casing from above will not enter the passageway 14 but will fall down about the housing 4.

The head 11 also has a bore 17, from the upper end downwardly therethrough into the float chamber 5 and whose lower end is reduced forming an inside annular shoulder 18. Fitted within this bore there is a tubular valve casing 19, whose lower end fits against said shoulder. The upper end of the bore 17 may be closed by a plug 20, which abuts the upper end of the valve casing.

The valve casing 19 has a lateral opening 21 which registers with the inlet passageway 14, and above and beneath the opening 21 are the inside annular downwardly converging valve seats 22, 23, with which the upper and lower disc-like valves 24, 25 cooperate. These valves are secured in fixed relation in any preferred manner. As shown, the upper valve 24 is secured to the upper end of the valve stem 26 and the lower valve 25 is fitted onto said stem. There are the tubular upper and lower spacers 27, 28 around the stem 26 the former of which is interposed between and spaces said valves and the latter of which is arranged beneath and abuts the valve 25 and is retained in place by the nut 29 which is threaded onto the stem 26 and abuts the lower end of the spacer 28. The spacers 27, 28 have the respective longitudinal guide wings 30, 31, thereon and spaced apart therearound whereby the valves 24, 25 are maintained centered relative to their respective seats. Above the valve 24 the casing 19 has the lateral opening 32 which registers with the passageway 33 leading through the head 11 into the float chamber 5. As shown in Figures 3 and 4 the valves 24, 25 are in closed position and the operating fluid will be cut off from the float chamber 5. From an inspection of Figure 4 it will be apparent that the transverse diameter of the valves 24 and 25 is somewhat less than the transverse diameter of the valve casing 19 and the areas of the valves exposed to the pressure of the operating fluid, when the valves are closed, are approximately equal and the valves will be balanced by said pressure so that the total pressure of the operating fluid will not have to be overcome in opening the valves, thus conducing to the easy opening of said valves.

The upper end of the casing 1 has a conventional casing head 34 attached thereto having packing 35 supported therein around the eduction tube 12. Above said packing there is a suitable adapter 36 in said casing head having an inside downwardly converging slip seat 37 and in this seat are the conventional wedge shaped slips 38 which engage and support the eduction tube 12. The adapter 36 and slips 38 may rest against the packing 35 to maintain the same compressed and to form a fluid tight joint with the casing head and eduction tube to prevent the escape of the operating fluid from the casing 1. The adapter and slips may be maintained in

position by means of the cap 49 secured on the casing head. Any preferred type of casing head may be employed with means thereon for supporting the eduction tube and for forming a seal at the top of the casing 1. The casing 1 is thus sealed by the packing 3 beneath the fluid elevating apparatus and by the packing 35 at the upper end of the casing thus forming a compression chamber 50 within the casing around the eduction tube 12 in which the operating fluid may be maintained under the required pressure. This operating fluid is supplied from a suitable source, such as a compressor, through the line 51 which may be equipped with a suitable gauge 52 for registering the amount of the compression in the chamber 50.

The eduction tube 12 leads off to a suitable receptacle to receive the liquid discharged from the well and the pressure line 51 is connected into the eduction tube 12 by means of a suitable connecting pipe 53 which is formed of sections connected by a suitable coupling 53'. The pipe 53 is equipped with a gauge 54 and between this gauge and the pipe 51 there is a suitable gate valve 55 connected into the pipe 53 and normally closed. The eduction tube has a suitable gate valve 55' incorporated therein out beyond the connection of the pipe 53 with said eduction tube, said valve 55 being normally open but being provided to close the eduction tube when it may be desired to do so. The head 11 also has a relief passageway 56 which connects the bore 13 with the chamber 5 and whose inner or lower end is flared forming a seat 57 which is controlled by the inwardly opening valve 58. This valve 58 is attached to the upper end of the stem 59 and the upper end of this stem works through a suitable guide 60 in the passageway 56, said end being extended for that purpose.

Depending from the head 11 there is a suitable anchor 61 and a valve actuating lever 62 is pivoted at one end to this anchor 61 and its other end is provided with a bifurcated yoke 63 whose fingers work in suitable side bearings in the bearing member 64 attached to the lower end of the stem 26. The lower end of the stem 59 is pivotally connected to the lever 62 at an intermediate point of said lever. Pivoted to the lower end of the anchor 61 there is a bell crank having the arms 65, 66. The arm 65 extends out across the chamber 5 and has the depending actuating rod 67 whose upper end is pivotally connected to the free end of the arm 65. A cross link 68 has its upper end pivoted to the lever 62 between the yoke 63 and the point of connection of the stem 59 to said lever 62. The other end of the cross link 68 has a slidable pivotal connection with the arm 65. The arm 66 depends beneath the anchor 61 and its free end is connected to said anchor by means of pull springs 69, 69.

Within the float chamber 5 there is a float 70 and extending longitudinally through this float, at one side of its longitudinal axis, there is a tube 71 whose ends are secured to the ends of the float. This tube forms a loose bearing through which the eduction tube 12 extends, said tube forming also a guide for said float. The float is of the required buoyancy and has the upstanding rod 72 whose upstanding end has an overturned yoke 73 which has a bearing to receive the rod 67.

Longitudinally adjustable on the rod 67 are the upper and lower stops 74, 75 spaced the required distance apart, the former above the yoke 73 and the latter being beneath said yoke. Be-

neath the float 70 the eduction tube 12 has the upper and lower disc like supports 76, 77 on the former of which a dash pot is secured. This dash pot is of novel construction and comprises 5 a cylinder 78 whose lower end is closed by a cap 79 which is fastened to the supporting disc 76. Attached to the upper end of the cylinder 78 there is a closure cap 79 having the ducts 80, 80 leading outwardly therethrough and having an axial bearing 81. Within the cylinder 78 there is a plunger 82 which is attached to the lower end of the plunger rod 83. This plunger rod works through the bearing and its upper end is pivotally connected to the lower end of 10 the float 70. The cylinder 78 is filled with a liquid 84 of high specific gravity, preferably mercury. The plunger 82 has the passageways 85 extending longitudinally therethrough and a back pressure valve 86 normally closes these passageways and has a leak duct 87 therethrough. The valve 86 opens downwardly and is supported by a stem 88 which extends up into the plunger and whose upper end has an enlarged head 89. A coil spring 90 surrounds said stem 88 and is 15 interposed between the head 89 above and the annular shoulder 91 of the plunger beneath. The spring 90 normally acts to hold the valve 86 closed. Upon upward movement of the plunger 82 the valve 86 will readily open to permit the 20 passageway of the mercury through the passageways 85 so that said liquid will offer slight resistance to the upward movement of said plunger and float. Upon downward movement of said plunger the valve 86 will be closed and the liquid 25 in the cylinder 78 beneath the plunger will be restricted to the duct 87 and the downward movement of the plunger and float will accordingly be retarded.

The inside diameter of the lower end of the cylinder 78 is enlarged as at 92. The plunger 82 fits snugly in the cylinder above this enlarged lower end of the cylinder and upon downward movement of the plunger, when the plunger fully enters said enlarged portion, the liquid beneath 40 the plunger may pass also up around said plunger and the downward movement of the plunger and float will be accelerated.

Attached to and depending from the lower end of the float 70 there are the guide rods 93, 93, which work through suitable bearings 94, 95, of the upper and lower discs 76, 77 and these guide rods have their lower ends connected by a cross bar 96. There is a counter balance weight 98 in the lower end of the float chamber which is supported by the chain 99. One end of this chain is attached to the weight and the chain, or other flexible member, works over a pulley 100, rotatably mounted on a bracket 101, which is attached to and depends from the under side of the disc 77. The other end of this chain is attached to the cross bar 96. The float 70 is preferably hollow and formed of metal and of sufficient strength to prevent crushing by the pressure to which it is subjected, although any selected type of float 55 may be used. The float is not necessarily of itself buoyant, but when counter balanced by the weight 98, will rise as the level of the liquid in the chamber 5 rises but its descent will be retarded by the dash pot hereinabove described and for the purpose hereinafter stated. Mercury is preferably used in the dash pot for the reason that it is desirable, in order to conduce to the free operation of the dash pot, not to form a close joint between the rod 83 and closure cap 79 and liquid in 60 the float chamber will freely enter and be dis-

charged through the ports 80 but this liquid will float on the mercury as also any foreign matter that may be contained therein; and also for the reason that the viscosity of the mercury will not appreciably vary as a result of the temperatures to which it may be subjected in a well and the resistance it offers to the plunger 82 will be approximately the same at all of said temperatures.

In use, the apparatus is lowered into a producing well to the required distance beneath the liquid level so that the liquid in the well will rise and enter the chamber 5, as the liquid is expelled therefrom as hereinafter stated.

An operating fluid, either gas or air, is forced into the casing chamber 50, through the pressure line 51 and the operating fluid is maintained under pressure in said casing. The liquid rising through the pipe 2 will lift the valve 8 and enter the float chamber 5 and the float 70 will be elevated and will carry the yoke 73 upwardly with it, 10 and when said yoke 73 strikes the stop 74 the rod 67 will be lifted. A very slight movement of the rod 67 upwardly will elevate the free end of the arm 65, the lateral pin 102 carried by said arm 65 moving in the oblong slot 103 in the link 8 until the arm 66 has been moved inwardly to carry the springs 69 past center and thereupon said springs will impart a sudden thrust to the link 68 which in turn will suddenly elevate the free end, or yoke 63, of the lever 62 and this 20 will cause a sudden upward movement of the valve stem 26. The valves 24, 25 will offer slight resistance to this upward movement for the reason that, as before stated, they are approximately balanced by the pressure of the operating fluid. 25 These valves 24, 25 will accordingly be opened and when lifted from their respective seats the operating fluid will pass around the valves and enter the chamber 5 both through the reduced lower end of the bore 17 and through the passageway 33. As the lever 62 is actuated upwardly the relief valve 58 will close the relief passageway 56, and will limit the opening movement of the valves 24, 25. Thereupon, the pressure of the operating fluid against the load of liquid in the 40 chamber 5 will drive said liquid into and through the eduction tube 12 to the ground surface where the liquid will be discharged through a suitable discharge line 104 provided for the purpose, and constituting a continuation of the tube 12. 50

As the liquid is expelled from the chamber 5, the float 70 will descend, but it is necessary that the descent of the float be retarded so that the valves 24, 25 will not be prematurely closed and the operating fluid cut off from the chamber 5 before the load of liquid has been completely expelled to the ground surface and for this purpose the dash pot hereinbefore mentioned has been provided. As explained, this dash pot offers little resistance to the elevation of the float by 55 reason of the fact that the valve 86 will freely open upon elevation of the plunger 82, but as the float 70 descends the valve 86 will remain closed and the liquid beneath said valve will pass through the leak duct or port 87 into the cylinder 78 above said valve thus retarding the descent of the float until the plunger 82 passes within the enlarged lower end 92 of the cylinder 60 65 whereupon the liquid beneath said plunger may pass freely upwardly about the plunger permitting a sudden acceleration of the downward movement of the float 70 whereupon the yoke 73 will strike the stop 75 causing a downward movement of the rod 67 and the arm 65 and the corresponding outward movement of the arm 66 70 75

carrying the springs 69 back across center and imparting a sudden downward thrust to the link 68 thereby opening the relief valve 58 and operating through the stem 26 to close the inlet valves 24, 25. The operating fluid offers a minimum resistance to the closing movement of the valves 24, 25 by reason of the fact that the stream of the inflowing operating fluid is divided and acts substantially equally against both valves in opposite directions.

It is to be noted that the elevator will be located at different depths in different wells and the time required for expelling a load will vary according to the depth, accordingly the stops 74, 75 must be adjusted for depth so that after the float has been elevated to open the valves 24, 25 its descent will not be completed and said valves closed and the operating fluid cut off until the load has been completely expelled.

When the inlet valves 24, 25 are closed and the relief valve 58 opened, the float chamber 5 will be substantially empty and at this time the weight of the float 10 and of the counter balancing weight 98 are supported from the lower stop 75 so that, until the float is again lifted, these valves will be securely maintained in this last mentioned position.

Thereupon, the liquid from the producing formation of the well may again enter the chamber 5 until another load of liquid has entered said chamber and any air or gas in said chamber above may freely pass out through the relief passageway 56 into the eduction tube 12. Meanwhile the operating fluid will be cut off so that there will be no waste of said operating fluid while the float chamber is being filled with liquid. The float 10 will accordingly again be lifted as before, and when another load of liquid has been entrapped in the chamber 5 the valves 24, 25 will again be opened and the valve 58 be closed as above explained and the operating fluid will again enter the chamber 5 and expel the load of liquid entrapped therein, and the operation of entrapping the loads of liquid in the float chamber and expelling the same from the chamber to the ground surface will be automatically repeated in succession so long as the operating fluid is maintained under the required pressure in the casing and so long as the well produces sufficient liquid to collect in successive loads in the float chamber as the same are expelled therefrom.

The drawings and description disclose what is now considered to be a preferred form of the invention for the purpose of showing a way in which the invention may be used, but the inventive thought upon which the application is based, is broader than the illustrative embodiment thereof and I therefore intend no limitations other than those imposed by the appended claims.

60 What I claim is:

1. In apparatus for raising predetermined loads of liquid, successively, from a well to the ground surface, liquid entrapping means having a chamber provided with an inlet for an operating fluid under pressure and a relief outlet, a valve controlling the inlet, a relief valve controlling the outlet, an eduction tube leading from the chamber, a float arranged to be elevated by the entrapped liquid and operative, when elevated, to effect the opening of the inlet valve and the closing of the relief valve, whereby the operating fluid is admitted into the chamber to expel the load from said chamber through said tube, and operative when lowered to effect the closing of the inlet valve and the opening of the relief valve, a dash

pot containing mercury which acts to retard the downward movement of the float to maintain the inlet valve open until the entrapped load of liquid is discharged from the well.

2. In apparatus for raising predetermined loads of liquid, successively, from a well to the ground surface, liquid entrapping means having a chamber provided with an inlet for an operating fluid under pressure and a relief outlet, a tube leading from said chamber out of the well, a valve controlling said inlet, a relief valve controlling the outlet, a float arranged to be elevated by the entrapped liquid and operative, when elevated, to effect the opening of the inlet valve and the closing of the relief valve, whereby the operating fluid is admitted into the chamber to expel the entrapped load through said tube and operative, when lowered, to effect the closing of the inlet valve and the opening of the relief valve, a dash pot containing a liquid having a higher specific gravity than that of the entrapped liquid or the operating fluid and which acts to retard the downward movement of the float to maintain the inlet valve open for a predetermined time after the entrapped load of liquid is discharged from the chamber, and means connecting the float and valves which is adjustable to vary the interval between the opening and the closing of the valves in accordance with the time required to discharge a load.

3. In apparatus for elevating loads of liquid, successively, from a well, liquid entrapping means having a chamber provided with an inlet for an operating fluid under pressure and a relief outlet, a valve controlling said inlet, a relief valve controlling the outlet, a discharge line leading out of the well from said chamber, a float arranged to be elevated by the entrapped fluid and operative when elevated, to effect the opening of the valve to admit operating fluid to expel the load and to close the relief valve, and operative, when lowered, to effect the closing of the inlet valve and the opening of the relief valve, a dash pot containing mercury arranged to retard the downward movement of the float and to thereby delay the closing movement of the inlet valve for a predetermined length of time after the entrapped load has been expelled from the chamber.

4. In apparatus for elevating loads of liquid, successively, from a well, liquid entrapping means having a chamber provided with an inlet for an operating fluid under pressure and a relief outlet, a valve controlling said inlet, a relief valve controlling the outlet, a discharge line leading out of the well from said chamber, a float arranged to be elevated by the entrapped fluid and operative when elevated, to effect the opening of the valve to admit operating fluid to expel the load and to close the relief valve, and operative, when lowered, to effect the closing of the inlet valve and the opening of the relief valve, a dash pot containing mercury arranged to retard the downward movement of the float and to thereby delay the closing movement of the inlet valve for a predetermined length of time after the entrapped load has been expelled from the chamber, and a counter balance in the chamber for the float.

5. An apparatus for expelling liquid from a well comprising liquid entrapping means having a chamber for the liquid, and shaped to be lowered into a well, an eduction tube leading out of the well from said chamber, said liquid chamber having an inlet to admit an operating fluid into the chamber to expel the entrapped liquid

through said tube from the well, said chamber also having a relief outlet, an inlet valve controlling said inlet, a relief valve controlling the outlet, a pivotally mounted valve actuating lever having a connection with the inlet valve and the relief valve, a float in said chamber, a pivotally mounted bell crank to one arm of which the float is connected, a pull spring attached at one end to an anchor and at its other end to the other arm of the bell crank, a link connecting the valve actuating lever and bell crank whereby upon elevation of the float said spring will be rendered effective to open the inlet valve and close the relief valve and upon downward movement of the float, the spring will be rendered effective to close the inlet valve and open the relief valve.

6. In apparatus for raising predetermined loads of liquid successively from a well to the ground surface, liquid entrapping means having a chamber provided with an inlet for an operating fluid

under pressure, and a relief outlet, a tube leading from said chamber out of the well, a valve controlling said inlet, a relief valve controlling the outlet, a float arranged to be elevated by the entrapped liquid and operative, when elevated, to effect the opening of the inlet valve and the closing of the relief valve whereby the operating fluid will be admitted into the chamber to expel the entrapped load through said tube, and operative when lowered to effect the closing of the inlet valve and the opening of the relief valve, means effective to retard the downward movement of the float to maintain the inlet valve open for a predetermined time after the entrapped load of liquid is discharged from said chamber, and means connecting the float and valves, which are adjustable to vary the interval between the opening and the closing of the valves in accordance with the time required to discharge the load.

JEDDY D. NIXON. 20
